UNITED STATES PATENT OFFICE.

JOHN A. PEASE, OF SKANEATELES, NEW YORK, ASSIGNOR OF ONE-HALF TO WALLACE M. WEEKS, OF SKANEATELES, NEW YORK.

BOTTLE CLOSURE.

Application filed December 11, 1925. Serial No. 74,788.

This invention relates to improvements in bottle closures, designed particularly for closing and sealing the mouths of the common milk bottles, and has for its object to 5 provide a cap or closure, preferably made from paper stock, which comprises a reinforced disc-like central portion, that fits snugly into the recess of the bottle mouth, and a sanitary integral flexible apron or 10 flange, which closely overlies the flared portion above the annular ledge that usually supports the common disc stoppers. A further object is to stencil or print letters upon the said apron, which may represent the 15 milk vendor's initials, or other symbols or characters suitable for identifying a dealer's products; the said markings preferably being applied at a number of points and adjacent the perimeter of the cap. And a 20 further object is to apply an adhesive to the underside of the flexible apron at a number of points adjacent the margin of the apron, preferably at or near the stenciled or printed characters, for positively sealing and 25 preventing the ruffling or distortion of the apron by handling, and for excluding dirt and germs, as well as obviating the danger of unauthorized persons removing or otherwise tampering with the original closure, or 30 extracting or substituting the contents of the bottle without detection; the said adhesive preferably being odorless and tasteless, and of such nature that a satisfactory 35 seal may be effected by utilizing the moisture that usually collects upon the surface of the flaring mouth during the filling of the bottle; the said adhesive being so disposed that the sealing of the closure may be effected by the parts of the filling machine that 40 apply the caps to the filled bottles. It being an object of the present invention to include the application of heat to the flexible flange of the closure, for softening the adhesive, in case the latter requires higher than normal 45 temperature for effecting the ready and positive sealing of the cap.

This invention relates particularly to improvements of the closures shown and described in the pending joint application, filed August 31, 1925, Serial No. 53,689.

The various features and parts of the invention will be understood from the detailed description which follows, and by ref-

erence to the accompanying drawing, in which—

Figure 1 is a central vertical section, showing the cap applied to a milk bottle, the section of the cap being taken on line 1—1 of Fig. 2. Fig. 2 is a top-plan view of the cap, showing the flexible flange stenciled with initials; also showing dotted circles indicating location of the adhesives. Fig. 3 is a bottom face view of the cap; showing points where adhesive is applied; also showing printed initials by dotted lines. Fig. 4 is a similar view; showing the stencil initials staggered relatively to the adhesive. Fig. 5 is a broken view of a cap; showing stencil initials, but no adhesive. Fig. 6 is a bottom plan view of a plain cap, upon which the adhesive extends unbroken around the flange. And Fig. 7 is a central vertical section, taken on line 1—1 of Fig. 2.

In the drawing, 2 represents the neck of an ordinary milk bottle. 3 is the flaring mouth, and 4 represents the annular shoulder or ledge, that forms the bottom of the recess, in which the closure is usually disposed.

In the present case, the closure for the bottle, follows generally the construction and arrangement shown in the pending application, and comprises a disc-shaped central body 5, having a diameter substantially equal to the diameter of the recess and the ledge 4, the said body being formed with an integral relatively broad flexible apron or flange 6, which is folded inwardly, at its junction with the disc 5, for providing an annular socket or groove 6', the said apron then being folded outwardly for providing a relatively broad annular convex portion 6^a, preferably made from a disc of relatively light or thin gage tough paper stock, which may be readily folded and molded, as shown in Fig. 7, by means of suitable dies, and whose flange or apron 6^a may be readily unfolded, and the portion 6^a flared to correspond to the flare of the neck 2 above the recess, as shown in Fig. 1. The disc 5 is preferably dished or depressed, as at 5^a, for stiffening the same, and for resisting upward or outward flexing, by the weight of the contents of the bottle, or by the expansion of air, which is usually confined in the void, as 2', by the quick and forcible insertion of

the closure, as shown in Fig. 1. The depression 5^a is surrounded by a plane annular margin 5^b, that seats firmly upon the ledge 4. In order to effect the ready folding and 5 rolling of the main cap, as shown and described, the gage of the paper is preferably about the same as ordinary ledger bond, (shown thicker in drawing for clearness), and owing to the extreme lightness of the 10 material, the disc 5 requires suitable reinforcing for preventing the disc from being unduly flexed or distorted during the capping operation. To this end, a circular member 7 is provided, which may be made 15 from pulp or tag board of relatively heavy gage for stiffening the portion of the cap that actually effects the liquid seal of the bottle mouth. The central portion of the member 7 is preferably correspondingly 20 dished, as at 7', and intimately engages the disc 5. The member 7 is formed with a plane margin 7^a, which is partially received in and is gripped by the infold of the flange 6, whereby said member is firmly held in 25 place before, as well as after the cap is applied to the bottle mouth.

In practice it has been found that owing to the extreme thinness of the web of the convex flange 6^a, the free margin of the latter tends to spring away from the flared surface of the mouth, when the bottle is roughly handled, thereby admitting dust or germs to the surface over which the contents of the bottle are poured. To overcome this unsanitary condition, and also to provide against unauthorized removal of the cap, or tampering with the contents of the bottle, I provide simple and effective means for sealing the said flange, which consists of applying to, or coating the concave underside of the apron 6^a, with a suitable adhesive, such as parafin, gum arabic compounds, or other odorless and tasteless material, the said adhesive preferably being applied at two or 45 more points and adjacent the periphery of the cap, as shown at 8, in Figs. 2, 3 and 4. This point-sealing has proven very effective for holding the relatively light gage apron in close contact with the flared mouth, and 50 when an adhesive of the proper character is employed, it is impossible for the apron to be loosened, without tearing or otherwise defacing and showing that the cap has been tampered with. The shaded portions 8 and 55 8' in Figs. 3, 4 and 6, show different ways of applying the adhesive. This adhesion of the apron to the bottle may be effected by various means according to the peculiar nature of the adhesive, as by wetting the mouth 60 of the bottle, or by applying heat immediately after the cap has been forced into the mouth. When the adhesive consists of gum arabic, and certain other ingredients it has been found that the moisture that usually 65 collects upon the surface of the bottle mouth

during the filling operation readily and quickly softens the adhesive, and it only requires that suitable pressure be applied to the apron, in order to effect the positive sealing of the parts, as described.

Another object of the invention is to provide novel means for identifying the products of the dealers. This is accomplished in an extremely simple yet effective manner, by stenciling or printing letters, as "N," which may stand for "Netherland," or "S" for "Syracuse" or "Smith," at or near the free margin of the apron 6^a, as shown in Figs. 2, 3, 4 and 5. The stenciling or printing of the letters, and the spots of the adhesive, may coincide, as shown in Figs. 2 and 3, or the initials may be staggered relatively to the adhesive, as shown in Fig. 4. When the adhesive is in the form of a relatively heavy wax, it is preferably applied at the 70 stencil points, where the margin of the apron is weakened by cutting out the letters, and in case heat is required to soften the wax, the letter openings facilitate the quick melting of the wax, as well as the capillary spreading of the same beneath the apron. Either the initials or the adhesive may be used alone, if desired, as shown in Figs. 5 and 6. Where a thin layer of the adhesive is employed, it may be applied to the underside of the caps when they are made, like envelopes are treated. When the heavier waxes are employed, they may be applied in the form of wafers, or the wax in proper 80 viscous state may be applied by the machine 90 that performs the capping operation.

By the use of the adhesive, as herein shown and described, a much thinner sheet or web of paper stock may be employed for the larger member of the closure, which is very desirable, inasmuch as it enables the apron 6^a to be more readily flexed against the flared portion of the mouth, and the provision of the letters or other characters denoting initials of the dealers, not only serve 95 to identify the products contained in the bottles, but when the said characters are stenciled, as shown in Fig. 2, and the adhesive is applied so as to coincide with the stencils, any attempt to remove the closure 100 by breaking the several seals, results in tearing and mutilating the apron and showing 105 tampering.

Having thus described my invention, what I claim, is—

1. A bottle closure comprising a disk having an annular apron adapted to overlie the upper edge of a bottle, said apron having perforations forming marks of identification adjacent the marginal edge along the circumference thereof and adhesive applied to the under side of the apron whereby a tight seal between the upper edge of the bottle and apron is obtained.

2. A bottle closure comprising a disk hav-

- ing an annular apron adapted to overlie the upper edge of a bottle, said apron having marks of identification providing weakened portions adjacent the marginal edge and spaced from each other and adhesive applied to the under face of the apron and extending into said weakened portions whereby mutilation of the cap is obtained when an attempt is made to remove the same.
- 10 3. A bottle closure comprising a disk having an annular apron adapted to overlie the upper edge of a bottle, said apron having

perforations forming marks of identification at spaced intervals throughout the circumference thereof, and adhesive applied to the under face of the apron and extending upwardly into the perforations to provide an added anchorage for the adhesive and to further seal the perforations whereby to prevent the passage of dust therethrough and the accumulation of the same upon the upper edge of the bottle.

In testimony whereof I affix my signature.
JOHN A. PEASE.
